UNITED STATES PATENT OFFICE.

ZOLLI COFFER FONVILLE, OF RALEIGH, NORTH CAROLINA.

CLOTHESPIN.

1,367,181.

Specification of Letters Patent.

Patented Feb. 1, 1921.

Application filed January 3, 1920. Serial No. 349,146.

To all whom it may concern:

Be it known that I, ZOLLI COFFER FONVILLE, a citizen of the United States, and a resident of Raleigh, in the county of Wake and State 5 of North Carolina, have made certain new and useful Improvements in Clothespins, of which the following is a specification.

This invention relates to new and useful improvements in clothes pins of that type in 10 which a pair of jaws are held in a normally closed position by means of a spring.

It is the object of this device to provide a 15 spring bridle of simple and efficient construction by means of which the jaw members are held in clamping relation.

In the accompanying drawing forming part of this specification:

Figure 1 is a top elevation of my improved clothes pin.

20 Fig. 2 is a side elevation thereof, and,

Fig. 3 is a perspective view of the spring bridle.

A pair of clamping jaws 1 substantially 25 rectangular in cross section are each provided near their end with confronting transverse recesses forming an oval recess 2 for engagement with a clothes line. At the opposite end of these clamping jaws the inner surfaces are outwardly tapered to form 30 the handle portion 3. Transverse slots 4 and 4' are provided across the exposed faces of the clamping jaws at diametrically opposite points.

The spring bridle is preferably formed of 35 a single piece of resilient wire formed so as to constitute a straight intermediate portion 5 which is interposed between the clamping jaws where it acts as a fulcrum for the same. Parallel arms 6 and 6' extend at right 40 angles to this intermediate portion for engagement with opposite sides of said clamping pieces and terminate in inwardly directed portions 7 and 7' for engagement with slots 4 and 4' on the outer surfaces of the 45 clamping members, thus presenting smooth unobstructed sides which prevent injury to clothes or other garments. Rearwardly extending portions 8 and 8' are bent substantially at right angles to members 7 and 7' 50 and parallel to side engaging members 6 and 6' and engage opposite sides of the clamping jaws.

In assembling the device the tapered end 3 of one clamping jaw is inserted between the 55 cross members 7 and 7' and is moved rearwardly and above the intermediate portion

until the cross piece 7 engages slot 4. The tapered end of the other clamping jaw is then inserted between the underside of the other clamping piece and the cross piece 7' 60 and forced rearwardly under intermediate portion 5 until inwardly projecting cross piece 7' engages slot 4'. It will be observed that the formation of this spring bridle in the manner described forms a central portion to act as a fulcrum for the movement of the clamping jaws and also provides top and side engaging members which tend to hold the jaws in a normally closed position and which are so disposed as to prevent any 65 lateral displacement of the two clamping jaws with respect to each other.

There is an important feature to be observed in connection with the formation of the spring bridle in the manner above specified. It is almost universally the practice to 70 employ coils of various descriptions for producing the spring tension which normally holds the jaws in a closed position. In this respect, this clothes pin is distinctive. The 75 intermediate or bridge portion 5 not only acts as a fulcrum as stated above, but becomes the spring for closing the jaws when put under a twisting or torsional strain when the jaws are opened.

When it is desired to fasten clothes on a line the clamping members are grasped at their oppositely tapered ends and are pressed inwardly thus forcing the clamping ends apart against the tension of the spring 80 bridle and permitting the engagement of the clothes line. As soon as the pressure on ends 3 is released the bridle forces the clamping ends together thus gripping the garment and clothes line. In order to remove the pin it is only necessary to exert an inward pressure on ends 3 of the clamping jaws thus opening the opposite ends and at the same time pull upward on the clothes pin when the garment may be detached.

100 I claim:

1. A clothes pin comprising a pair of clamping jaws, and a wire bridle including an intermediate portion between the jaw members and forming a fulcrum therebetween, and having ends extending to points of fastening at the gripping ends of the jaw members, the spring tension produced in said intermediate portion being applied at said points of fastening when the jaws are 110 separated.

2. A clothes pin comprising a pair of

clamping jaws and a wire so mounted therebetween to act as the fulcrum and spring for holding the jaws in closed position, the latter by virtue of the twisting strain created therein when the jaws are separated.

3. A clothes pin comprising a pair of jaws, and a wire bridle with ends secured including a single strand between the jaws, forming a fulcrum and exerting spring tension when the jaws are opened and said strand is put under a torsional strain.

4. A clothes pin comprising a pair of jaws, clamping means composed of a wire bent in substantially one plane into a rectangular form with free ends overlapping 15 and to be respectively secured to the jaws, the side of the rectangular form opposite said overlapping ends constituting the fulcrum and spring for the clothes pin when put under torsional strain by the separation 20 of said free ends.

ZOLLICOFFER FONVILLE.
